UNITED STATES PATENT OFFICE.

CHARLES R. HAYNES, OF NAUGATUCK, CONNECTICUT, ASSIGNOR TO THE GOODYEAR'S METALLIC RUBBER SHOE CO., A CORPORATION OF CONNECTICUT.

DESIGN FOR A SOLE.

52,217.

Specification for Design.

Patented July 23, 1918.

Application filed March 6, 1916. Serial No. 82,499. Term of patent 7 years.

To all whom it may concern:

Be it known that I, CHARLES R. HAYNES, a citizen of the United States, residing at Naugatuck, county of New Haven, and State of Connecticut, have invented a new, original, and ornamental Design for Soles, of which the following is a specification, reference being had to the accompanying drawing, forming a part thereof.

The figure is a perspective view of a sole showing my new design.

I claim:

The ornamental design for a sole as shown.

Signed at Naugatuck, county of New Haven, and State of Connecticut, this 2nd day of March, 1916.

CHARLES R. HAYNES.
